UNITED STATES PATENT OFFICE.

HYMAN MAIMIN, OF NEW YORK, N. Y.

MOTOR DRIVE FOR SEWING MACHINES.

Application filed February 14, 1924. Serial No. 692,915.

To all whom it may concern:

Be it known that I, HYMAN MAIMIN, a citizen of the United States, residing at New York city, in the county of New York, State of New York, have invented certain new and useful Improvements in Motor Drives for Sewing Machines; and I do hereby declare the following to be a full, clear, and exact description of the invention, such as will enable others skilled in the art to which it appertains to make and use the same.

This invention relates to a variable speed motor drive for sewing machines.

In my copending application, Serial No. 670,881; filed October 26, 1923, I have described and claimed a variable speed motor drive for sewing machines, in which I employ a constantly running single speed motor having a truncated cone driving pulley, and a loose pulley adjacent the small end of the cone and of substantially the same diameter. Variations in the sewing machine speed are obtained by moving the driving belt along the face of the cone. As the belt moves up the enlarging face of the cone not only does the gear ratio increase but the slippage of the belt decreases so that these two factors cooperate to speed up the machine. The present invention contemplates certain improvements and refinements in the drive of the earlier application, although utilizing the same principles of operation. These improvements relate to the gear-shifting mechanism, the brake which is applied when the belt is shifted onto the loose pulley, and to the bracket which supports the motor, and its associated mechanism. These improvements will be described in connection with the accompanying drawings, illustrating certain preferred embodiments thereof, and more particularly pointed out in the appended claims. In these drawings, Fig. 1 is an elevation of the sewing machine equipped with the motor drive of the present invention, the driving belt being shown passing about the loose pulley and in inoperative position; Fig. 2 is an end elevation of the part shown in Fig. 1; Fig. 3 is a section through the two pulleys taken along line 3-3 of Fig. 2; Fig. 4 is a similar section taken along line 4-4 of Fig. 2; and Fig. 5 is a section taken along line 5-5 of Fig. 2 through parts of the belt-shifting means but showing the pulleys in elevation.

In Fig. 1 a conventional sewing machine

is shown mounted upon a table 2, and provided with usual pulley 3 and handwheel 4. The driving unit is situated immediately below the table and supported by a bracket 5, which depends from the lower face of the table and is bolted thereto. The motor 7 and the belt-shifting and braking mechanism are carried by this bracket. Power is transmitted to the machine by means of a belt 6, which passes through suitably positioned holes in the table.

Mounted upon the spindle 10 of the motor are two pulleys, a fast cone pulley 11 and a loose pulley 12 provided with ball bearings (see Figs. 3 and 4). The loose pulley is mounted adjacent the small end of the cone pulley and is of slightly less diameter than said small end, thus forming a small shoulder 13 at the place where the pulleys meet. This shoulder, however, is only slight and does not prevent the belt from being moved from the loose pulley onto the face of the cone pulley, but it does effectively prevent any unintended movement of the belt onto the cone pulley, and also serves to more effectively impart the initial driving power to the belt. As shown, the loose pulley is provided with a slightly tapered or conical face. Any tendency of the belt to slip off this pulley is counteracted by the well known tendency of belts to creep up toward that part of the pulley having the largest diameter (hence crowned pulleys), and will also be prevented by one of the elements of the gear shifting means to be described later. The angle of the cone face of the fast pulley is such as substantially to align itself with the face of the loose pulley, with the exception of the very small shoulder formed at the junction of these two pulleys as described above. The base of the cone pulley is provided with an annular seat 14 having a groove 15 in its middle. The cone pulley is also provided at its base with a flange 16 which makes it impossible for the belt to move off its seat on that side. The driving unit is positioned so that the base 14 of the cone pulley is in substantially the same plane as the pulley 3 on the sewing machine so that when the sewing machine is being driven at maximum speed the belt 6 shall be run in a single plane. At this point, the belt is stretched to its maximum tautness.

In order to move the belt from the loose pulley to the fast pulley and hold it upon any desired position of the cone, I have pro-

vided a novel and improved belt-shifting mechanism, which I shall now describe. The bracket 5 is provided at one side with a plate 18 which extends at right angles 5 from the motor supporting face of the bracket. This plate is provided with two parallel bores 19 in which the moving frame of the belt-shifting mechanism is designed to slide. This frame comprises a pair of rods 21 united by a crosshead 22, which slides along a fixed rod 20 extending from the forward end of the plate 18. Extending inwardly from the crosshead 22 are three arms 23, 24 and 25; upon the second of 15 which, arm 24, is journaled a roller 26. These elements are so positioned that the arm 23 is located on one side of the belt and the roller 26 and the arm 25 on the other, as shown most clearly in Fig. 4. The 20 arm 23 and the roller 26 are also so positioned relative to the belt that in both extreme positions, there is a slight clearance between them and the belt. Upon the other end of the rod 20 extending beyond the plate 25 18 is mounted a bell crank lever 27 to one end of which is connected a rod 28 operated by treadle 29, while the other end abuts against a collar 31 fixed upon the outer end of the upper rod 21. A second collar 32 is 30 fixed upon this rod 21 beyond the other end of the plate 18 and serves to limit the inward movement of the belt-shifter frame. Encircling the fixed rod 20 and bearing against the plate 18 and crosshead 22, a compression 35 coil spring 33 is located, which constantly urges the crosshead away from the plate 18.

In accordance with the present invention, I have also provided novel and improved means for braking the sewing machine when the belt has been moved into 40 inoperative position upon the loose pulley. A brake arm 34 is pivotally mounted upon the outer and upturned end of the fixed rod 20. One end of this arm carries an arcuate 45 brake shoe 35, designed to contact with the inner face of the rim of the loose pulley, as shown most clearly in Fig. 3. The other end of this arm is designed to contact through a set screw 36 with the outer end 50 of the belt-shifting frame, as also shown most clearly in Fig. 3.

The operation of the drive may be described and briefly reviewed as follows:— The motor is constantly running so that the 55 fast pulley 11 is constantly rotated at uniform speed. Starting from the position of rest shown in Fig. 1 with the belt encircling the loose pulley, the operator bears upon the treadle, and through the connection rod 28 60 and the bell crank lever 27 moves the belt-shifting frame to the left, as shown in Fig. 1. This movement brings the roller 26 into contact with the belt and moves it into contact with the shoulder 13 on the pulley 11. As the belt is loose when in this posi-

tion, there is considerable slippage and only a very slow motion is imparted to the sewing machine. If higher speeds are desired, the operator presses the treadle farther down and moves the belt along the encircling face 70 of the cone pulley; thus decreasing the slippage at the same time that the gear ratio is increased. At full speed the belt rides upon the grooved base of the fast pulley. To decrease the speed or stop the machine, pressure on the treadle is relieved and the spring 75 33 immediately moves the belt-shifting frame toward the right; this movement bringing the arm 23 into contact with the belt and forcing it from the seat 14. In 80 initiating the driving movement should the belt tend to lag and not respond to the pressure of roller 26 around the entire contacting periphery of the pulley, the arm 25 which immediately follows the roller 26 85 gives the lagging belt the necessary pressure to force it into alignment. Movement of the belt-shifting frame into its extreme right hand position with the belt wholly upon the loose pulley brings the frame into contact with the set screw 36 and automatically applies the brake. The loose pulley is thus 90 instantly held fixed and there is sufficient frictional engagement between it and the belt, and the belt and the sewing machine 95 pulley to prevent further rotation of the latter.

I claim:

1. In a motor drive for sewing machines, the combination of a motor having a fast 100 and a loose pulley, means for shifting a driving belt from one pulley to the other, and means operated by the belt shifting means for braking the loose pulley when the belt is shifted thereupon.

2. In a motor drive for sewing machines, the combination of a motor having a fast and a loose pulley, means for shifting a driving belt from one pulley to the other, and a brake arm pivoted adjacent the loose 110 pulley, having a shoe on one end adapted to contact with the loose pulley, the other end being actuated by the belt-shifting means to apply the brake when the belt is shifted upon the loose pulley.

3. In a motor drive for sewing machines, the combination of a motor having a fast and a loose pulley, means for shifting a driving belt from one pulley to the other, and a brake arm pivoted adjacent the loose 120 pulley, having an arcuate shoe on one end adapted to contact with the inner face of the rim of the loose pulley, the other end being actuated by the belt-shifting means to apply the brake when the belt is shifted 125 upon the loose pulley.

4. In a motor drive for sewing machines, the combination of a motor having a fast and a loose pulley, means for shifting a driving belt from one pulley to the other, a 130

- brake arm pivoted adjacent the loose pulley, having a shoe on one end adapted to contact with the loose pulley, the other end being actuated by the belt-shifting means to 5 apply the brake when the belt is shifted upon the loose pulley, and a set screw in that end of the arm contacting with the belt-shifting means.
5. In a motor drive for sewing machines, 10 the combination of a motor having a fast cone pulley and a loose pulley adjacent the small end of the cone pulley and of substantially the same diameter, and a belt shifter for shifting a driving belt from one pulley to 15 the other comprising means for moving the driving belt up the inclined face of the cone pulley, and means spaced slightly beyond the moving means for preventing lagging of the belt.
- 20 6. In a motor drive for sewing machines, the combination of a motor having a fast cone pulley and a loose pulley adjacent the small end of the cone pulley and of substantially the same diameter, a belt shifter for 25 shifting a driving belt from one pulley to the other comprising means for moving a driving belt up the inclined face of the
- cone pulley, means spaced slightly beyond the moving means for preventing lagging of the belt, and means on the other side of 30 the belt for moving the belt down the face of the cone.
7. In a motor drive for sewing machines, the combination of a motor having a fast cone pulley and a loose pulley adjacent the 35 small end of the cone pulley and of substantially the same diameter, a belt shifter for shifting a driving belt from one pulley to the other comprising a roller for urging the belt up the inclined face of the cone 40 pulley, an arm following the roller for preventing lagging of the belt, and an arm on the other side of the belt for moving the belt down the face of the cone pulley, the two arms and the roller being mounted upon 45 a sliding frame.
8. A support for the motor drive of claim 7, comprising a bracket designed to depend from the under face of the sewing machine table and provided with a housing for the 50 sliding belt-shifter frame.

In testimony whereof I affix my signature.

HYMAN MAIMIN.
